TYPEWRITING MACHINE

Filed Feb. 17, 1928

2 Sheets-Sheet 2

UNITED STATES PATENT OFFICE

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK

TYPEWRITING MACHINE

Application filed February 17, 1928. Serial No. 255,006.

It is very common in power driven typewriting machines to have all instrumentalities of the machine, such as the type action, escapement mechanism and ribbon mechanism, operated by power and to have this operation controlled by a slight depression of the key lever. This slight depression of the key lever constitutes the whole of the work that is performed by the operator, the remainder thereof being performed by the power mechanism.

In certain type actions, particularly that embodied in the standard Royal machine, the amount of work involved in actuating the type action to bring the type bars to the printing point is very slight, the greatest amount of work is that involved in the operation of the escapement and the ribbon mechanism.

The present invention relates to mechanism wherein the type action is operated manually in the usual manner while the escapement mechanism and ribbon mechanism are operated by power. All of these elements and the lever which operates the same may be the same as the usual corresponding instrumentalities in the standard Royal machine. The operating lever, however, is not operated from any part of the type action as has previously been the case, but there is provided a universal bar which initiates the operation of the power mechanism and the power mechanism actuates the operating lever to thereby produce proper movements of the escapement and ribbon mechanisms.

This invention is in many respects very similar to that shown and claimed in my prior application No. 242,165 filed Dec. 23, 1927, which matured July 30, 1929, into Patent No. 1,722,937. Claims common to the subject matter of both cases are placed in the prior application while the present invention covers features of construction not shown in the earlier case.

In the drawings:

Figure 1 is a fore and aft section with parts in elevation showing the normal position in full lines and an intermediate position of certain parts in dotted lines.

Figure 2 is a similar view showing the

parts in the position which they occupy immediately preceding the contact of the type bar with the platen.

Fig. 3 is an elevation of the universal showing details of construction.

Fig. 4 is a plan view of Fig. 3.

The present invention may be embodied in typewriting machines of widely different character but for the purpose of illustration it has been shown in connection with a standard Royal typewriter. The drawings disclose a portion of a shift frame A upon which travels a carriage B provided with the usual platen C against the front of which strike type bars D which are pivoted in the usual segment E. Key levers F are connected by links G to front links H which in turn are connected by links I to the type bars D. The usual escapement mechanism K is employed and the usual ribbon vibrator M with its actuator N. An operating lever L is positioned to actuate the escapement and ribbon vibrator in the usual manner and is returned by the usual spring against the adjustable stop member. All of these parts are such as are commonly employed in the Royal machine but this showing is to be regarded merely as illustrative and not as in any way limiting the invention.

The universal bar 1 is freely mounted in a slot 2 formed in the segment E and the front edge of the bar is adapted to be engaged by the type bar at a point near the pivot thereof and during the printing movement of the bar to move said bar rearwardly. The ends of the bar 1 are pivotally connected as at 3, 3 to the upper ends of arms 30, 30 of bell crank levers 31 which are fixed to a rock shaft 4. An arm 5 of one of the bell crank levers 31 is pivotally connected to one end of a link 6, the other end of the link being pivotally connected to the intermediate portion of a lever 7 which is pivoted at one end as at 8 to the machine frame 32.

The universal bar 1 is provided with two rearwardly extending and horizontally disposed rigid supporting arms 33, 33. One of the arms 33 is pivotally connected at its rear end as at 34 to the upper end of a lever 35 which is fulcrumed on the main frame. The

other arm 33 is pivotally connected at its rear end as at 36 to the upper end of an arm 37 of a bell crank lever 38 which is pivoted at its angle as at 39 to the machine frame. 5 The pivots 4 and 39 are in the same horizontal plane. The arms 30 of the bell crank levers 31, the lever 35 and the arm 37 of the bell crank lever 38, are all of the same radii, and consequently the universal bar 1 is movable bodily in a fore and aft direction and in 10 a substantially straight line located in a horizontal plane.

The bell crank lever 38 is provided with a 15 forwardly extending arm 40 to which one end of a coil spring 41 is connected, the other end of said spring being secured to a fixed part of the machine frame. Thus when the universal bar 1 is moved rearwardly under impact of a type arm, said bar together 20 with the horizontal supporting arms 33, 33 will be moved rearwardly in a substantially horizontal plane, said movement rocking the bell crank levers 31 and 38 against the tension of the spring 41. Consequently when 25 the type bar begins its return movement, the spring 41 will function to return the universal bar 1 and the bell crank levers 31 and 38 to their initial positions.

The other end of the lever 7 is adapted to 30 operate a trip member 23 which controls power mechanism X and permits the same to come into operative engagement with a constantly rotating shaft Y. This mechanism is substantially the same as that shown 35 in patent to Dorsey No. 1,628,037 of May 10, 1927, and needs no further detailed description herein. It may be noted that the trip member 23 is substantially or exactly the same as the member designated by that reference numeral in the above-cited patent. This 40 power mechanism has been selected for illustration although it is obvious that some other form of power mechanism might be employed so long as it is brought into operation 45 by the movement of the lever 7.

The movement of the power mechanism will swing a bell crank lever 9 which is pivoted at 10 on a frame member 11 which supports the entire power unit. This bell crank 50 lever is connected by an adjustable link 12 with the operating lever L above described.

Whenever a key lever F is depressed, a 55 type bar will be moved to printing position in the usual manner. As the type bar reaches the dotted line position of Figure 1 it contacts with the universal bar 1 and the movement of the latter throws the power mechanism into operation. By the time the type bar is moved 60 from the dotted line position of Figure 1 to the full line position of Figure 2 the power mechanism has substantially completed its operation and the operating lever L has actuated the ribbon vibrator and the escapement mechanism has been given the first part of its 65 to and fro movement.

Since the power mechanism is immediately disconnected as soon as it completes its operative movement, it is obvious that the operating lever L, escapement mechanism and ribbon mechanism will at once return to their 70 normal positions and the type action will be returned to its normal position by the usual springs upon releasing the pressure from the key lever. It is apparent that this invention 75 provides a construction which will afford an extremely light action and will permit of exceedingly rapid operation of the machine. Various details of construction may obviously be varied without in any way departing 80 from the spirit of the invention, which is to be regarded as limited only by the scope of the appended claims.

I claim as my invention:

1. In a typewriting machine embodying a type bar, an operating lever, and escapement 85 and ribbon mechanism actuated by said lever; the combination of a key lever for operating said type bar, a universal bar which is moved by direct engagement of the type bar, a rock shaft, supporting arms fixed on said rock 90 shaft and pivotally connected to the respective ends of the universal bar, power operated devices, operative connections between the power operated devices and the operating lever, and operative connections between the 95 supporting arms and the power operated devices for bringing the latter into operation upon movement of the universal bar.

2. In a typewriting machine embodying a type bar, an operating lever, and escapement 100 and ribbon mechanism actuated by said lever; the combination of a key lever for operating said type bar, a universal bar which is moved by direct engagement of the type bar, a rock shaft, supporting arms fixed on said rock 105 shaft and pivotally connected to the respective ends of the universal bar, spaced arms extending rearwardly from the universal bar, pivotally mounted supporting arms respectively pivoted to the rear ends of the rearwardly extending arms, said pivoted supporting arms being of the same radius whereby the universal bar will be moved in a substantially horizontal plane, power operated devices, operative connections between the 110 power operated devices and the operating lever, and operative connections between one of the supporting arms and the power operated devices for bringing the latter into operation upon movement of the universal bar.

In testimony whereof, I have hereunto subscribed my name.

LEWIS C. MYERS.
